UNITED STATES PATENT OFFICE.

HENRY PRICE, OF NEW CASTLE, PENNSYLVANIA.

LATRINE-MOLDING SYSTEM.

1,109,636.

Specification of Letters Patent. Patented Sept. 1, 1914.

Application filed January 29, 1913. Serial No. 744,996.

To all whom it may concern:

Be it known that I, HENRY PRICE, a citizen of the United States, residing at New Castle, in the county of Lawrence and State 5 of Pennsylvania, have invented a new and useful Latrine-Molding System, of which the following is a specification.

The present invention discloses a mold of novel form, adapted to fashion in one piece, 10 the bowl of a water-closet and the lower, tubular extension thereof.

One object of the present invention is to provide a structure of this type in which an opening exists in the bottom of the bowl, 15 above the spoon, novel means being provided for closing the opening, after the spoon has been fashioned.

Another object of the invention is to provide novel means for forming the spoon.

20 The invention aims, further, to provide novel means for forming and for assembling with the spoon, elements which co-operate to form the end wall and the upper wall of the outlet for the bowl.

25 The invention aims, further, to provide a novel process for forming the spoon and for closing an opening in the bowl above the spoon.

It is within the scope of the invention to 30 present a novel process whereby the end wall and the upper wall of the outlet for the bowl are assembled with the spoon.

The invention aims, further, to improve generally, and to increase the utility of 35 molds whereby water closets are formed.

It is within the scope of the invention to improve generally, the process whereby the water closet is formed, and to improve the several steps of such a process.

40 With the foregoing and other objects in view which will appear as the description proceeds, the invention resides in the combination and arrangement of parts and in the details of construction hereinafter described and claimed, it being understood that 45 changes in the precise embodiment of the invention herein disclosed, can be made within the scope of what is claimed, without departing from the spirit of the invention.

50 In the drawings:—Figure 1 shows a vertical longitudinal section, of a water closet constructed in accordance with the present invention; Fig. 2 is a transverse section of the structure shown in Fig. 1; Fig. 3 is a 55 perspective view showing the main mold

sections spaced apart; Fig. 4 is a perspective view of the spoon-forming mold; Fig. 5 is a perspective of the L-shaped mold which is employed for forming the upper wall and the end wall of the outlet or siphon of the 60 bowl; Fig. 6 is a perspective of the member which is inverted upon the elements shown in Fig. 3, to effect a closure of the opening which exists in the bottom of the bowl; Fig. 7 is a fragmental perspective of the ring which is connected with the upper rim of the bowl; Fig. 8 is a perspective of the base of the complete structure; and Figs. 9, 10, 11 and 12, are transverse sectional views illustrating several steps in the process here- 70 matter described.

The bowl portion of the closet is fashioned in a pair of main mold sections denoted by the numeral 1 as shown in detail in Fig. 3. One of these sections 1 upon its inner face, 75 is provided with openings 2, adapted to receive bosses 3 which outstand from the inner face of the other main mold section 1, the parts 2 and 3 co-operating to prevent the main mold sections 1 from sliding upon each other and from changing their relative positions. The main mold sections 1 are duplicates, and each section is provided with an upper recess 4 and a lower recess 5, there 80 being a passage 6 extended between the recesses 4 and 5. The line at which the upper recess 4 merges into the passage 6 is indicated by the reference character 7. Surrounding the upper end of the recess 4 is an 85 annular groove 8 and radial grooves 9 communicate with the groove 8. At the back of each main mold section 1 is formed a radial groove 10 which is deeper than the grooves 9. A superficial recess 11 opens into the groove 10 and communicates with the 90 annular groove 8. The recesses 4 and the 95 passages 6 are lined with plastic material, in a sufficiently stiff condition to be worked readily by the fingers or by a tool, this plastic material being indicated by the reference character 12 in Fig. 9. The two mold sections 1 are then brought into abutting relation, the bosses 3 registering in the openings 2. The plastic material 12 is then 100 caused to coalesce, by pressure or otherwise, along the lines 14 which indicate the places of abutment between the inner faces of the sections 1.

The operation above described serves to 105 fashion the bowl 18 and its depending tubu- 110

lar extension, the front wall of the bowl being indicated by the reference character 15 in Fig. 1 and the rear wall of the bowl being indicated by the reference character 16, the 5 reference characters 17 serving to indicate, in Fig. 2, the side walls of the completed structure and the bowl being indicated generally by the reference character 18. By the 10 operation above described, an opening 19 10 (referring to Fig. 9) will be left in the bottom of the bowl 18, the periphery of this opening being defined by the lines 7, as will be understood best when Fig. 3 is examined.

The structure, as thus far completed, 15 comprises the bowl 18 and its tubular, depending extensions, and the next step, ordinarily, is to apply the spoon which, in Fig. 1, is denoted by the reference character 28. In carrying out this step in the process, there 20 is employed a spoon mold, shown in Fig. 4 and denoted generally by the numeral 20. The spoon mold 20 comprises a pallet 21, secured to which is a base 22. This base 22 is shaped to correspond with the base of the 25 finished product, the base of the finished product being shown in Fig. 8 and being designated by the reference character 23. Upstanding from the base 22 of the spoon forming mold 20 is a pedestal 24 which is adapted 30 to fit in the passage 6. The pedestal 24 at its upper end extends but part way across the passage 6, in the direction of the longer dimension of the passage, in order that an outlet may be provided at the front of the 35 structure, as will be understood readily from Fig. 1. The upper end face of the pedestal 24, indicated at 25, is concaved both longitudinally and transversely.

A section of plastic material, indicated 40 at 26 in Fig. 11, is placed upon the end face 25 of the pedestal 24 and is compacted to approximate the curvature of the end face 25. The main mold sections 1 are then superposed upon the pallet 21, the base 22 45 of the spoon-forming mold 20 registering in the lower recess 5 and the pedestal 24 extending upwardly into a passage 6. By this operation, the material indicated at 26 and carried by the end face 25 of the pedestal 50 24 will be positioned to form the spoon 28, shown in Fig. 1, the pedestal 24 serving to compact the tubular portion of the water closet in the passage 6. The material indicated at 26 is then compacted manually so as 55 to cause the same to coalesce with the depending tubular portion of the bowl, along the lines indicated at 27 in Fig. 10. By this operation, the spoon 28 is mounted in place, one end of the spoon 28 being joined up 60 with the rear wall 16 as indicated at 29 in Fig. 1. It is now necessary to complete the upper wall of the outlet 100, indicated at 38 in Fig. 1, and to complete the end wall 39 of the outlet, and to join these parts to the 65 spoon 28 so that siphon may be completed.

In carrying out this step in the invention, there is employed the mold which is shown in Fig. 5.

The mold shown in Fig. 5 is denoted generally by the numeral 30 and may, for convenience, be denominated the siphon mold. The mold 30 comprises a pallet 31, provided with a base 32, corresponding in outline to the base 23 of the finished product as shown in Fig. 8. Secured to and upstanding from the base 32 is an L-shaped element 33 comprising a body 34 and an upstanding stem 35, one end of the body 34 being rounded off as shown at 36. A mass of plastic material which, in Fig. 11, is indicated by the numeral 37, is placed upon the body 34 of the L and upon the stem 35 of the L and is compacted upon these elements, to conform to the desired shape. The main mold sections 1 are then lifted off the spoon mold, the parts being positioned as shown in Fig. 10. The main mold sections 1 are then placed upon the mold section 30, the parts appearing as shown in Fig. 11. By this operation, the mass of material 37 which is carried by the L 33 is thrust upwardly into the passage 6 and unites with the spoon 28 to form the end wall 39 of the outlet and to form the upper wall 38 of the outlet, reference being had to Fig. 1. A chamber 40 will be formed at the rear end of the wall 38, where the same joins the rear wall 16, this chamber 40 resulting from the fact that one end of the body 34 is curved or rounded as indicated at 36. Furthermore, there will be formed another chamber 41, defined by the wall 38, the wall 39 and the spoon 28. During the baking operation, of course, the chambers 40 and 41 are punctured to permit the steam and heated air to escape, thereby avoiding a 95 bursting of the structure. It now remains to close the opening indicated at 19 in the bowl 18. In carrying out this step, there is employed a bowl closing mold shown in Fig. 6 and designated by the reference character 42. The bowl closing member 42 comprises a pallet 43 provided with radial ribs 44 and with a cap 45. Projecting from the cap 45 is a rib 46, the edge of which is inclined as indicated at 47, the rib 46 being 100 equipped at one end with a boss 48. A piece of plastic material indicated at 49 is applied to and worked down upon the inclined end face 47 of the rib 46. The bowl closing member 42 is then inverted and is placed upon the main bowl sections 1, the ribs 44 registering in the grooves 9 and the cap piece 45 registering in the groove 8. The plastic material indicated at 49 is received in a rabbit 50 formed in the bowl 18 around the 105 periphery of the opening therein and is joined up with the constituent material of the bowl, to form the bottom closure 51, one end of the closure, indicated at 52, being determined by the boss 48 and the other end 110 115 120 125 130

of the closure being connected up with the wall 15, as indicated in Fig. 1. The bowl closing member 42 is then removed, leaving the material 49 in place to form the closure

5 51. The base indicated at 23 and shown in Fig. 8 is inserted into the lower recess 5 of the main mold sections and a ring 53, shown in Fig. 7, is assembled with the upper edge of the bowl, the ring 53 having a hinge lug 54 extending into the recess 11, the hinge lug 54 being provided with an inlet 55 registering in the deep groove 10. The main mold sections 1 may then be removed and, the structure will appear as depicted in Fig.

10 15 1. The device is permitted to dry out and, after a sufficient period of time has elapsed, is baked in the usual manner.

Attention is directed to the fact that the water closet herein disclosed is a one piece structure from top to bottom. Owing to the fact that the opening 19 is left in the bowl, and owing to the fact that this opening 19 is not closed until the mold section 42 is applied, access may be had readily to the interior of the water closet, for the purpose of closing joints and finishing up the structure.

Having thus described the invention, what is claimed is:—

30 1. The herein described process of fashioning a water-closet body, which consists in forming the bowl peripherally leaving an opening in the bottom of the bowl; mounting a spoon in place below the opening; and closing the opening.

2. The herein described process of fashioning a water-closet body, which consists in forming the bowl in a mold, leaving an opening in the bottom of the bowl, charging a member with material and inserting the member into the mold; removing the member and leaving the material to form the spoon, charging a second member with material and superposing the second member upon the mold to cause the material thereon to register in the opening, and removing the second member, leaving the material in the opening.

3. The herein described process of fashioning a water-closet body, which consists in forming the bowl and the spoon into an integral structure within a mold, leaving an opening in the bottom of the bowl, charging an L-shaped member with ma-

55 terial and inserting the L-shaped member into the mold; removing the L-shaped member and leaving the material in contact with the spoon to form the upper wall and the end wall of the outlet from the

60 bowl; charging a second member with material and superposing the second member

upon the mold to cause the material thereon to register in the opening; and removing the second member, leaving the material in the opening.

4. The herein described process of fashioning a water-closet body, which consists in forming the bowl in a mold, leaving an opening in the bottom of the bowl; charging a member with material and inserting the member into the mold; removing the member and leaving the material to form the spoon; charging an L-shaped member with material and inserting the L-shaped member into the mold; removing the L-shaped member and leaving the material carried thereby in contact with the spoon to form the upper wall and the end wall of the outlet from the bowl; charging a third member with material and superposing the third member upon the mold to cause the material thereon to register in the opening; and removing the third member, leaving the material in the opening.

5. The herein described process of fashioning a water-closet body, which consists in forming the bowl and the spoon into an integral structure within a mold; charging an L-shaped member with material and inserting the L-shaped member into the bowl; and removing the L-shaped member, leaving the material in contact with the spoon to form the upper and end walls of the outlet for the bowl.

6. The herein described process of fashioning a water-closet body, which consists in forming the bowl in a mold; charging a member with material and inserting the member into the bottom of the mold; and removing the member, leaving the material in contact with the bowl to form the spoon.

7. The herein described process of fashioning a water-closet body, which consists in forming the bowl in a mold; charging a member with material and inserting the member into the bottom of the mold; removing the member and leaving the material in contact with the bowl to form the spoon; charging an L-shaped member with material and inserting the L-shaped member into the bottom of the mold; and removing the L-shaped member, leaving the material carried thereby in contact with the spoon to form the upper wall and the end wall of the outlet for the bowl.

In testimony that I claim the foregoing as my own, I have hereto affixed my signature in the presence of two witnesses.

HENRY PRICE.
